FAN

Masaetsu Hagiwara, São Paulo, Brazil

Application December 14, 1948, Serial No. 65,241
In Argentina November 11, 1948

2 Claims. (Cl. 230—268)

1. This invention relates to fans and more particularly to that type of fans generally known as folding fans having accordion webs.

The principal object of my invention is to provide folding fans which when folded the webs are entirely concealed within the handles and as examples thereof I have illustrated in the accompanying drawings two highly satisfactory forms thereof of varying design but both incorporating the primary features of my invention.

Another object of my invention is to provide such fans which include simple and inexpensive operating parts of highly efficient and practical construction, and pleasing in appearance.

Another object of my invention is to provide such a fan which when extended the web will have a substantial spread with a large area positively but yieldably held in spread or open position and when closed the webs will be entirely concealed in a comparatively short handle having a length only slightly in excess of the length of the radial folding web portions.

Still further objects, details and advantages of my invention will appear in the following specification supplemented by the accompanying drawings forming a part thereof and illustrating highly satisfactory embodiments thereof.

In the drawings:

Fig. 1 is a front elevation view with parts broken away of a fan in an open condition in accordance with my invention.

Fig. 2 is an edge elevation thereof.

Fig. 3 is a front elevation of the fan handle, the fan web being entirely concealed within the handle.

Fig. 4 is an edge elevation thereof.

Fig. 5 is a detail plan view of the web and associated parts.

Fig. 6 is a bottom end view thereof.

Fig. 7 is an enlarged fragmentary side elevation of one of the web end parts.

Fig. 8 is an enlarged vertical sectional view thereof taken on line 8—8 of Fig. 7.

Fig. 9 is an enlarged transverse sectional view through the fan handle taken on line 9—9 of Fig. 1.

Fig. 10 is an enlarged fragmentary sectional view of the handle taken on line 10—10 of Fig. 2 with other parts shown in broken lines.

Fig. 11 is an enlarged fragmentary plan view of the fan web supporting end parts.

Fig. 12 is an elevation thereof parts being broken away along lines 12—12 of Fig. 11.

Fig. 13 is a plan view of the spring retaining member shown in Figs. 11 and 12.

Fig. 14 is a front elevation view of a slightly modified form of fan in accordance with my invention.

Fig. 15 is a plan view of the web and associated parts.

Fig. 16 is an enlarged fragmentary vertical sectional view of the fan handle.

5. In general this invention relates to a fan consisting of a hollow handle 20 into which folding webs 21 can be drawn and completely enclosed or concealed as best shown in Figs. 3 and 4 and when pushed out a spring 22 will operate to spread the fan web from its folded condition to its expanded position ready for use as shown by the examples Figs. 1 and 14. There are, of course, many shapes and designs of fans made of various materials, with stronger and weaker frames, with blades of paper or starched tissue or with light tissue fitted out with ribs. Also the handle and its upper part which forms the fan center can have various appearances. As examples are presented two fundamentally equal types but of different external shapes.

Referring particularly to the fan design illustrated in Figs. 1 to 13 inclusive it will be seen that the hollow handle 20 for the major part of its length is in general of rectangular cross section and each of its two side faces 23 has a midway longitudinal channel or slot 24 the length of which determines distance the fan web can be drawn into the handle. Each of the two side faces 23 has an enlarged extension 25 of fanciful design which covers a limited area of the fan web 21 and its associated parts; in this handle the end portions 26 are flared outwardly at their upper ends 27 and connect the lower portions of extensions 25, thereby providing abutments for the associated fan web parts as will hereinafter be described. The lower closed end of handle 20 is shown provided with a strap or eyelet 28 through which a carrying cord, ribbon or the like may be secured.

The fan webs 21 as shown in detached elevation and plan respectively in Figs. 5 and 6 comprise folding connected web sections or blades 29, the outer sides of the outermost of which are secured to substantially rigid bars 30. Bars 30 each terminates at its lower end with a pair of centrally apertured symmetrical side plates 31 and a transverse hook element 32 as shown in Figs. 7 and 8, respectively for the reception of a connecting and operating pivot member 33 which holds the bars in symmetrical alignment and also retains the spring 22.

As shown in Figs. 11 and 12 pivot member 33 passes through the apertures in the four side plates 31 as well as spring 22. Spring 22 is thus housed between the overlapping pairs of side plates 31 of the bar elements 30 and has ends 34 which engage the hook element 32 of one of

the side plates and an intermediate extending loop element 35 between two coiled torsion sections 36 which intermediate loop engages the hook 32 on the other side plate and operates to spread the fan webs 21 when they are withdrawn from handle 20.

Pivot member 33 extends beyond the side plates 31 and the ends pass through channels 24 terminating in enlarged buttons or heads 37 abutting the faces 23 of handle to maintain the fan webs 21 and its associated parts assembled in handle 20. These heads 37 also provide operating means for moving the fan webs 21 into and out of handle 20, the movement being determined by the length of channels 24. As shown in Figs. 1 and 2 the heads 37 are at the upper extremity of the channels 24, practically at the vertex of the various web sections or blades 29 convergence. By moving these pivot heads 37 downward to the other end of channels 24 spring 22 yields to the folding of the fan webs 21 and the latter is drawn down into the hollow handle 20 in an entirely concealed position, unless the fan web sections or blades 29 are designed and constructed to be of a greater length so as to afford a larger fan spread area, in which case the upper end of the fan webs may protrude above the enlarged extensions 25. Thus the opening and closing of the fan is effected by merely moving the heads 37 of pivot member 33 from one extremity of channels 24 to the other extremity which requires very little effort and spring 22 operates to effect the opening of the webs and readily yields to its closing.

As a guide means for the fan web side bars 30 and to facilitate opening of the fan webs 21 with a weaker spring member 22 than would otherwise be required, the hollow handle has longitudinal internal channels 38 along the side edges of the faces 23 and corresponding extensions 25 along the juncture with the connecting side edge portions 26 of handle 20 and the outwardly curved upper extensions 27 thereof. Bars 30, adjacent to their lower ends on each side, have projections 39 which cooperatively engage these grooves or channels 38. It will be seen by the broken line showing in Fig. 10 that when the fan web bars 30 are moved to their uppermost position the projections 39 on these bars must follow the groove 38 and are thereby swung to their open position for spreading the fan web 21 as shown in Fig. 1, and conversely when the bars are drawn down the channels operate on these projections 39 to swing the bars 30 to closed position folding the fan web sections or blades 29 upon each other so that the fan webs can be drawn into handle 20.

Referring to Figs. 14, 15 and 16, the fan illustrated is substantially the same except for design features and a few changes in details. It includes an internally grooved hollow handle 40 having channels 41 for fan side plate connecting pivot with operating heads 42. The upper face projections 43 are round as distinguished from the shape of projections 25. The fan web 44 as shown in plan in Fig. 15 has an upper conformation rounded instead of straight as shown in Fig. 5. Fan webs 44 have end bars 45 each with a pair of cooperating apertured hinge plates 46 for engagement on the pivot member and hook and spring elements may be employed though not essentially as projections 47 on bars 45 cooperating with grooves 41 operate to swing the bars outwardly when they reach the upper out-

wardly extending portions 48 of grooves 41 as shown in Fig. 16. It will be seen that in this arrangement the bars 45 are swung through a 90° angle so that the fan web 44 occupies a spread of 180° as compared with the lesser spread of fan webs 21 as shown in Figs. 1 and 10.

Having described the principles of my invention as applied to two highly practical forms of fans in accordance with my invention it is to be understood that my invention is not limited to the exact details of construction, the invention being defined in the following claims.

I claim:

1. A fan comprising interconnected folding fan webs, including outermost ones of said webs, bars connected to the outermost ones of said fan webs, at the sides of said outermost webs, and having lower ends, with pivot-accommodating perforations therein and edge projections with their axes substantially paralleling the axes of said perforations and disposed above the perforations, a pivot extending through said perforations and pivotally connecting the lower ends of said bars, a longitudinal hollow handle open at its upper end for receiving said fan webs and its end bars and having longitudinal channels therein through which the ends of said pivot extend as operating means for moving the fan webs into and out of the handle; and means for moving 20 the bars outwardly about said pivot when the webs are projected from the handle to spread the fan webs and for moving the bars toward each other to fold the webs into a flattened condition upon retraction of the pivot along the channels 35 in the handle to draw the fan webs into the handle comprising projections on the edges of said bars adjacent their connections with the pivot, and said hollow handle having longitudinal grooves flaring divergently outward at their upper ends for receiving said edge projections on the bars and guiding them in cooperation with the pivot for opening the bars as the pivot is moved to upper ends of the channels and to close upon a reverse movement of the pivot.
- 45 2. A folding fan comprising interconnected folding webs, including outermost ones of said webs, bars connected to the outermost ones of said webs and having edge projections extending transversely of the respective outermost ones 50 of said webs, a hollow handle having a compartment, an outer longitudinal open end to said compartment and grooves in said compartment flaring divergently outwardly to said outer end, with said projections snugly accommodated in said grooves and slidable therealong, and operating means extending into said compartment and connected with said webs for moving the webs into and out of said compartment.

MASAETSU HAGIHARA.
